COOKING APPARATUS FOR BAKING, GRILLING AND THE LIKE

Walter Koziol, Russell, Ill., assignor to Beatrice
Foods Co., Chicago, Ill.

Filed May 12, 1971, Ser. No. 142,842

Term of patent 14 years

Int. Cl. D7—02

U.S. Cl. D7—107

FIG.1

FIG.4

FIG. 1 is a perspective view of the cooking apparatus for baking, grilling and the like showing my design;

FIG. 2 is a front elevation thereof;

FIG. 3 is an elevation thereof as seen from the rear of FIG. 2; and

FIG. 4 is a top plan view thereof.

The elements shown in broken lines are included for illustrative purposes only.

I claim:

The ornamental design of a cooking apparatus for baking, grilling and the like, substantially as shown and described.
